(57) **CLAIM**

The ornamental design for a retainer for a sprayer wand, as shown and described.

DESCRIPTION

FIG. 1 is a first perspective view of a new and ornamental design for a retainer for a sprayer wand;

FIG. 2 is a front elevation view thereof;

FIG. 3 is a rear elevation view thereof;

FIG. 4 is a top plan view thereof;

FIG. 5 is a bottom plan view thereof;

FIG. 6 is a first side elevation view thereof;

FIG. 7 is a second side elevation view thereof; and,

FIG. 8 is a perspective view showing the retainer for the sprayer wand in use on a sprayer.

The sprayer and wand are shown in phantom for environment only and forming no part of the claimed design.
